TREATMENT OF HYDROCARBONS

William A. Myers, Springfield, Pa., assignor to
The Atlantic Refining Company, Philadelphia,
Pa., a corporation of Pennsylvania

No Drawing. Application July 18, 1936,
Serial No. 91,425

11 Claims. (Cl. 196—13)

The present invention relates to the art of mineral oil refining, and has particular reference to the separation of crude petroleum or petroleum products into fractions of different chemical composition while of approximately the same distillation range.

In accordance with my invention, crude petroleum or petroleum products, particularly oils of substantial viscosity, are separated into various fractions by extraction with a solvent mixture, and more particularly with a solvent mixture consisting essentially of nitrobenzene, nitrotoluene and diethylene-glycol mono-ethyl ether. In place of the glycol ether, there may be employed the alcohols such as methanol, ethanol and the like.

It is recognized in the art that mineral oils, such as petroleum, comprise essentially a mixture of hydrocarbons of various groups or homologous series of compounds, such for example, as paraffins of the general formula C_nH_{2n+2} , olefins of the general formula C_nH_{2n} , hydroaromatics and polymethylenes of the same empirical formula, and various other series of compounds of chain and/or ring structures in which the hydrogen to carbon ratio is less than in the foregoing series. A large number of individual compounds of each series and of differing boiling points are present in petroleum.

The various types of crude petroleum, which are generally classified into three groups, namely, paraffinic base, naphthenic or asphaltic base, and mixed base, contain the various series of hydrocarbons mentioned heretofore in different proportions. For example, in the paraffinic base crude oils, such as those obtained from the oil fields of Pennsylvania, there is a relatively high proportion of hydrocarbons having a chain structure and a high hydrogen to carbon ratio, whereas in the naphthenic or asphaltic base crude oils, there is a relatively large proportion of hydrocarbons having ring structures and a low hydrogen to carbon ratio. Mixed base crude oils, such as are obtained from the Mid-Continent oil fields, contain hydrocarbons in proportions intermediate between these two extremes.

The paraffin base oils and their distillates are said to be more paraffinic than the mixed base oils and their distillates and these in turn are more paraffinic than the naphthene base oils and their distillates. Conversely the naphthene base oils are more naphthenic than the mixed base oils and these in turn more naphthenic than the paraffinic base oils. The usual criteria of the degree of paraffinicity or naphthenicity of an oil

are the viscosity-gravity constant and the viscosity index. The viscosity-gravity constant is a constant relating viscosity and specific gravity and is described in an article entitled "The viscosity-gravity constant of petroleum lubricating oils" by J. B. Hill and H. B. Coates which will be found in vol. 20, page 641 et seq., of Industrial and Engineering Chemistry. Viscous oils resulting from the distillation of Pennsylvania type crudes have viscosity-gravity constants ranging from about .805 to .828, and in most instances are below .820. Those resulting from the distillation of Mid-Continent crudes have viscosity-gravity constants ranging from about .835 to about .855, whereas those from naphthenic crudes are generally higher than .860. The viscosity index is a coefficient based on the change of viscosity with temperature, and is described by Dean and Davis in vol. 36, page 618 of Chemical and Metallurgical Engineering. The more paraffinic oils are characterized by low viscosity-gravity constants and high viscosity indices, whereas the more naphthenic oils are characterized by higher viscosity-gravity constants and low viscosity indices.

My invention is based upon the discovery that oils containing both the paraffinic series of hydrocarbons and the various naphthenic series may be fractionally extracted with a selective solvent mixture consisting essentially of nitrobenzene, nitrotoluene and diethyleneglycol mono-ethyl ether. The various series of hydrocarbons possess a differential solubility in such solvent mixture, the naphthenic hydrocarbons being much more soluble therein than the paraffinic hydrocarbons. By means of extraction with such solvent mixture, it is possible to effect a partial separation of the naphthenic hydrocarbons from the paraffinic, and to obtain from an oil containing both classes of hydrocarbons, an oil which is much more paraffinic than the original oil and one which is much more naphthenic. By my invention, for example, it is possible to produce an oil of the quality normally obtained from Appalachian crudes, from crudes of the mixed base type from the Mid-Continent area or from those of the naphthenic base type and, conversely, to obtain oils from mixed base crudes or paraffinic base crudes such as are normally obtained from the naphthenic oils of the Gulf Coast area. In general, from oils from any source there may be obtained by my process, oils which are respectively more paraffinic and more naphthenic than the oils normally obtained from such source by distillation.

In accordance with my invention, I first mix the oil to be treated with a suitable proportion of a mixture of nitrobenzene, nitrotoluene and diethyleneglycol mono-ethyl ether at a temperature such that complete solution is effected and a homogeneous liquid obtained. I then adjust the temperature of the solution so that separation of the liquid into a two-layer system will take place. Such temperature is generally at least 35° F. 5 below the miscibility temperature of the oil and solvent mixture. One layer will contain a relatively small amount of the solvent mixture dissolved in the paraffinic portion of the oil (raffinate) while the other layer will contain the more 10 naphthenic portion of the oil (extract) dissolved in the major portion of the solvent mixture. Or, I may agitate the mixture of solvents and oil at temperatures at which the same are only partially miscible, and thereby effect solution of the 15 naphthenic portion of the oil in the solvent mixture. In either of the above procedures I may take advantage of the principles of countercurrent extraction.

After the extraction proper, I effect separation 20 of the two layers which form, by any suitable procedure, as for example, by decantation. I then remove from each of the separated layers, the portion of solvent mixture which each contains, by suitable procedure, such as by vacuum 25 distillation, thereby to obtain two oils of similar distillation ranges but of different chemical composition and different physical characteristics.

Before removing the solvent mixture from the 30 undissolved or more paraffinic layer, I may add a further quantity of the solvent mixture and repeat the extraction, thereby to remove additional naphthenic constituents from said layer. The extraction step may be repeated any desired number of times, each repetition producing an oil of 35 higher paraffinicity as evidenced by its lower viscosity-gravity constant.

A countercurrent relationship in these successive extractions may be established in the conventional manner by employing the partially 40 spent solvent mixture containing dissolved naphthenic oil from the succeeding stages of a batch-countercurrent extraction system to extract additional quantities of oil in the preceding stages, or in a continuous countercurrent system, the oil and solvent mixture may be simply flowed in 45 countercurrent contact with one another.

Where substantial quantities of waxy hydrocarbons belonging to the true paraffin series (C_nH_{2n+2}) are present, such hydrocarbons remain in the undissolved or more paraffinic layer 50 and may cause such layer to be solid or semi-solid, after the removal of the solvent mixture therefrom. In some cases, the extraction and separation of the layers may be effected at temperatures above the melting point of the waxy hydrocarbons, so that substantial entrainment of oil in the molten or liquid wax is avoided. Such layer may be separated into solid and liquid hydrocarbons by any of the well-known dewaxing 55 processes such as by cold-settling, filtering, or by centrifuging. In many instances it may be advantageous to dewax the oil prior to extraction. However, it is to be understood that in accordance with my invention, dewaxing may be effected either prior or subsequent to extraction.

I have found that solvent mixtures such as 70 nitro-benzene, o-nitrotoluene and diethyleneglycol mono-ethyl ether, or nitrobenzene, o-nitrotoluene and alcohol are of particular utility in the extraction of very naphthenic or asphaltic

base hydrocarbon oils, for example, lubricating oils from California crude oil. The particular solvent mixtures mentioned above have been found to be very satisfactory when employed in the extraction of oils of widely varying characteristics and under widely varying extraction conditions. The solvent mixtures of my invention may be employed under temperature conditions which are totally unsuitable for the use of any of the components of the mixture. For example, 5 nitrobenzene cannot be employed at temperatures lower than about 30° F., whereas my solvent mixtures may be utilized at temperatures of the order of 5° F. or lower. On the other hand, the extraction of some oil stocks with nitrobenzene 10 requires that the temperature be of the order of 35° F. or 40° F. to produce reasonable yields of refined oil of desired characteristics. By employing my solvent mixtures it is possible to effect satisfactory extraction of the same oil stocks at 15 temperatures, for example, of 70° F. to 80° F., thus effecting a marked economy from the standpoint of refrigeration. In general, the solvent mixtures of my invention are more flexible, or 20 may be of wider application, than any of the components of the mixtures used alone.

My invention will be further understood from the following specific examples:

1. An East Texas lubricating oil stock having a Saybolt Universal viscosity of 67 seconds at 210° F., an A. P. I. gravity of 22° at 60° F., and a viscosity-gravity constant of 0.860 was extracted in a 3-stage batch countercurrent extraction system at 5° F. with 75% by volume of a solvent mixture consisting of 56% nitrobenzene, 24% 35 o-nitrotoluol and 20% diethyleneglycol mono-ethyl ether. There was produced a raffinate oil fraction amount to 81.0% of the stock charged, such raffinate having a Saybolt Universal viscosity of 64 seconds at 210° F., an A. P. I. gravity of 25.2° and a viscosity-gravity constant of 40 0.836. The extract oil fraction amounted to 19.0% of the stock charged and had a Saybolt Universal viscosity of 158 seconds at 210° F., an A. P. I. gravity of 10.0°, and a viscosity-gravity constant of 45 0.945.

2. A Mid-Continent lubricating oil stock having a Saybolt Universal viscosity of 45 seconds at 210° F., an A. P. I. gravity of 26.0° at 60° F., and a viscosity-gravity constant of 0.846 was extracted in a 6-stage batch countercurrent extraction system at 5° F. with 40% by volume of a solvent mixture consisting of 56% nitrobenzene, 24% 55 o-nitrotoluol and 20% diethyleneglycol mono-ethyl ether. There was produced a raffinate oil fraction amounting to 84.3% of the stock charged, such raffinate having a Saybolt Universal viscosity of 43 seconds at 210° F., an A. P. I. gravity of 28.8° and a viscosity-gravity constant of 60 0.833. The extract oil fraction amounted to 15.7% of the stock charged and had a Saybolt Universal viscosity of 56 seconds at 210° F., an A. P. I. gravity of 11.5°, and a viscosity-gravity constant of 65 0.954.

3. A Gulf Coast lubricating oil stock having a 65 Saybolt Universal viscosity, of 198 seconds at 210° F., an A. P. I. gravity of 18.8° at 60° F., and a viscosity-gravity constant of 0.864 was extracted in a 3-stage batch countercurrent extraction system at 5° F. with 45% by volume of a 70 solvent mixture consisting of 56% nitrobenzene, 24% o-nitrotoluol and 20% diethyleneglycol mono-ethyl ether. There was produced a raffinate oil fraction amounting to 90.7% of the stock charged, such raffinate having a Saybolt 75

Universal viscosity of 158 seconds at 210° F., an A. P. I. gravity of 20.3° and a viscosity-gravity constant of 0.856.

4. A Mid-Continent residuum oil stock having a Saybolt Universal viscosity of 143 seconds at 210° F., an A. P. I. gravity of 20.8° at 60° F., and a viscosity-gravity constant of 0.853 was extracted in a 3-stage batch countercurrent extraction system at temperatures of 70° F., 77° F., and 85° F. in the 1st, 2nd, and 3rd stages, respectively, with 250% by volume of a solvent mixture consisting of 52.5% nitrobenzene, 22.5% o-nitrotoluol and 25% diethyleneglycol mono-ethyl ether. There was produced a raffinate oil fraction amounting to 54.1% of the stock charged, such raffinate having a Saybolt Universal viscosity of 92 seconds at 210° F., an A. P. I. gravity of 27.5° and a viscosity-gravity constant of 0.810. The extract oil fraction amounted to 45.9% of the stock charged and had a Saybolt Universal viscosity of 351 seconds at 210° F., an A. P. I. gravity of 12.7°, and a viscosity-gravity constant of 0.908.

From the above examples, it will be noted that by extraction of an oil with a solvent mixture comprising nitrobenzene, nitrotoluene and diethyleneglycol mono-ethyl ether, there may be obtained oil fractions which are respectively more paraffinic and more naphthenic than the original oil. By repetition of the extraction process upon the undissolved fraction, oils of even greater paraffinicity will result. The quantity of solvent mixture to be employed will vary, depending upon the character of the solvent mixture and the stock, the temperature at which the extraction is to be carried out, and the yield and quality of refined oil desired.

While, in the above examples, I have shown the use of solvent mixtures having specific ratios of nitrobenzene to nitrotoluene and the glycol ether, I do not intend to be limited thereto, but may employ any suitable proportions of the components, depending upon the results it is desired to achieve.

My process is practically independent of the particular nature or source of the crude oil or oil fraction to be extracted. There may be produced by my process oil products of desired characteristics from oil which by distillation will not produce such products.

When, in the appended claims, oil is referred to as being "viscous", it is to be understood that the oil is of substantial viscosity, i. e., of the order of 50 seconds Saybolt Universal at 100° F., or more. Likewise, herein and in the appended claims the term "o-nitrotoluene" is to be understood to include o-nitrotoluene and the isomers, m-nitrotoluene and p-nitrotoluene, and mixtures of the isomers containing a substantial proportion of o-nitrotoluene. The term "diethyleneglycol mono-ethyl ether" is to be understood to include "Carbitol", which is a commercial grade of diethyleneglycol mono-ethyl ether.

What I claim is:

1. In the art of refining minerals oils, the process which comprises separating an oil containing paraffinic and naphthenic hydrocarbons into fractions respectively richer in paraffinic and naphthenic compounds by extracting said oil with a solvent mixture comprising nitrobenzene, o-nitrotoluene and diethyleneglycol mono-ethyl ether.

2. In the art of refining mineral oils, the process which comprises adding a solvent mixture comprising nitrobenzene, o-nitrotoluene and di-

ethyleneglycol mono-ethyl ether to an oil containing paraffinic and naphthenic hydrocarbons, heating the mixture to such temperature as to effect solution, cooling the solution to form a two-layer system, and separating the upper layer from the lower layer.

3. In the art of refining mineral oils, the process which comprises adding a solvent mixture comprising nitrobenzene, o-nitrotoluene and diethyleneglycol mono-ethyl ether to an oil containing paraffinic and naphthenic hydrocarbons, heating the mixture to such temperature as to effect solution, cooling the solution to form a two-layer system, removing the lower layer, and similarly retreating the upper layer with said solvent mixture.

4. In the art of refining mineral oils, the process which comprises bringing a mineral oil containing paraffinic and naphthenic hydrocarbons into contact with a solvent mixture comprising nitrobenzene, o-nitrotoluene and diethyleneglycol mono-ethyl ether, thereby to effect solution of a portion richer in naphthenic hydrocarbons in the solvent mixture, separating the solution so formed from the remainder of the oil, and removing the solvent mixture from both portions of the oil, thereby to obtain fractions of the oil respectively richer in paraffinic and naphthenic hydrocarbons.

5. In the art of refining mineral oils, the process which comprises bringing a mineral oil containing paraffinic and naphthenic hydrocarbons into contact with a solvent mixture comprising nitrobenzene, o-nitrotoluene and diethyleneglycol mono-ethyl ether, thereby to effect solution of a portion of the oil richer in naphthenic hydrocarbons in the solvent mixture, separating the solution so formed from the remainder of the oil, and retreating the oil remaining with additional amounts of the solvent mixture.

6. In the art of refining hydrocarbon oils, the process which comprises bringing an oil containing paraffinic and naphthenic hydrocarbons into countercurrent contact with a solvent mixture comprising nitrobenzene, o-nitrotoluene and diethyleneglycol mono-ethyl ether, thereby to effect solution of a portion of the oil richer in naphthenic hydrocarbons in the solvent mixture, separating the solution so formed from the remainder of the oil and removing the solvents from the solution and the oil.

7. The method for producing paraffinic lubricating oil from mixed base oil, which comprises bringing the oil into contact with a solvent mixture comprising nitrobenzene, o-nitrotoluene and diethyleneglycol mono-ethyl ether, thereby partially dissolving the oil, separating the solution of oil so treated, and removing the solvent mixture from the treated oil.

8. The process of treating a viscous fraction of a crude oil of one type containing paraffinic and naphthenic hydrocarbons to procure a fraction having the quality of a corresponding fraction of a crude oil of different type having a greater content of paraffinic hydrocarbons, which comprises extracting the viscous fraction with a solvent mixture comprising nitrobenzene, o-nitrotoluene and diethyleneglycol mono-ethyl ether, and separating the oil so treated into portions respectively richer in paraffinic and naphthenic hydrocarbons.

9. The process of treating a viscous fraction of a mixed base crude oil to procure a fraction having the quality of a corresponding fraction of a paraffinic base crude, which comprises extracting the viscous fraction with a solvent mixture comprising

ing nitrobenzene, o-nitrotoluene and diethylene-glycol mono-ethyl ether, and separating the oil so treated into portions respectively richer in paraffinic and naphthenic compounds.

10. In the art of refining mineral oils, the process which comprises bringing a solvent mixture comprising nitrobenzene, o-nitrotoluene and diethylene-glycol mono-ethyl ether into intimate contact with a viscous hydrocarbon oil of a quality other than that of a Pennsylvania type viscous oil, and containing paraffinic and naphthenic components, thereby to dissolve from the oil sub-

stantial amounts of its naphthenic components, thereafter removing the solvent mixture and oil dissolved therein from that portion of the oil which remains undissolved, thereby to produce an oil such as is normally obtained from Pennsylvania type crude by distillation. 5

11. In the process of decreasing the viscosity-gravity constant of a viscous mineral oil, the step of extracting the oil with a solvent mixture comprising nitrobenzene, o-nitrotoluene and diethylene-glycol mono-ethyl ether. 10

WILLIAM A. MYERS.
